Specification for Design.

Patented June 11, 1918.

Application filed August 22, 1917. Serial No. 187,570. Term of patent 3½ years.

To all whom it may concern:

Be it known that I, ADOLPH M. HOLSTEIN, a citizen of the United States, residing at Syracuse, in the county of Onondaga and State of New York, have invented a new, original, and ornamental Design for a Manufactured Figure for Furniture and Casket Decorations and for Interior and Exterior Decorations, of which the following is a specification, reference being had to the accompanying drawing, forming a part hereof.

The drawing is a face view or front elevation of my design.

This design comprehends the representation of curved foliated scrolls curving upwardly and laterally and having foliated work extending along their upper portions,

the foliated work at the inner opposing ends of the scrolls curving about said ends, conventional foliated leaves joining the opposing ends of the scrolls and water droops hanging from the under sides of the scrolls.

I claim:

The ornamental design for a manufactured figure for furniture and casket decorations and for interior and exterior decorations, substantially as shown and described.

In testimony whereof, I have hereunto signed my name, at Syracuse, in the county of Onondaga, and State of New York, this 30th day of July, 1917.

ADOLPH M. HOLSTEIN.
